DOOR CLOSER

William J. Keene, Chicago, Ill., assignor to Chicago Spring Hinge Company, Chicago, Ill., a corporation of Illinois

Application July 18, 1936, Serial No. 91,272

5 Claims. (Cl. 16—76)

The present invention relates generally to devices for accomplishing the automatic closing of doors such as the doors for cold storage rooms, refrigerators, and the like.

5 The principal objects of the invention are to provide an improved door closer which shall be of a simpler and more rugged design than the structures heretofore known to the art and which shall have a much longer satisfactory operating life than those prior art structures; to provide an improved type of adjustable connection for use intermediate the door closer arm and the actuating spring therefor; to provide an improved, simplified structure for rendering the door closer inoperative when desired; and generally to provide an improved door closer.

These and other objects of the invention will be made more apparent in the accompanying drawing and the following description of a preferred embodiment of the invention. In the drawing—

Figure 1 is a fragmentary view illustrating the features of a door closer in accordance with the present invention in use upon the door of a cold storage chamber or the like;

Figure 2 is an enlarged elevational view, partially in section, of the door closer illustrated in Figure 1;

Figure 3 is a side elevational view, partially in section, of the door closer illustrated in Figures 1 and 2;

Figure 4 is a sectional view on the general line 4—4 of Figure 2;

Figure 5 is a sectional view on the general line 5—5 of Figure 2; and

Figure 6 is a plan view of the locking collar forming a part of the door closer illustrated in the other figures of the drawing.

Reduced to its simplest elements, the door closer of the present invention includes a horizontally extending closer arm 1 which is adapted to bear against the door 2 with which the device is used, and a spring assemblage 3 for biasing the closer arm in the proper direction. The closer arm 1 of the device illustrated in the drawing includes a main body or arm portion 4 which preferably comprises a suitable length of metal bar or rod and a metal head portion 5 to which the inner end of the arm portion 4 is securely attached, for example by being secured thereto as clearly shown in Fig. 4. The head portion 5 terminates in a hub 6 having a hexagonal opening 7 formed therein. The outer end of the closer arm 1 preferably rests against a roller 8 sup-

ported upon a U-shaped bracket 9 which is bolted or otherwise secured to the door 2.

The biasing spring assemblage 3 includes a cast upper or main frame 11 which is provided with three projecting frame parts or brackets 12, 13, 5 and 14, cast integral therewith in spaced relation. Coaxial cylindrical bearing openings, 15, 16, and 17, extend through these brackets for the purpose of supporting a short shaft 18 which is provided with three suitable bearing portions 10 15^a, 16^a, and 17^a for engaging respectively the bearing openings 15, 16, and 17. A suitable biasing spring 19 is securely connected at one end to a stub projection 20 integral with the shaft 18, and at its other end to another cast frame 21, 15 as illustrated in Figure 2. A cylindrical tube 24, preferably of metal, extends between the upper and lower frames 11 and 21 and serves to enclose the biasing spring 19. The tube 24 may be secured to the upper and lower frames by suitable means such as set screws as indicated in the drawing.

Intermediate the two bearing portions 15^a and 16^a of the shaft 18, the shaft is provided with a hexagonal section 22 which is adapted to non-rotatably fit in the hexagonal opening 7 in the hub of the closer arm. The hexagonal section 22 has a length approximately equal to one-half the distance between the lower bracket 12 and the central bracket 13, and above the hexagonal section 22 there is a rounded section 23 having a cross sectional area substantially less than the cross sectional area of the hexagonal section 22. As indicated in the drawing, the diameter of the rounded shaft section 23 is no greater than the 30 diameter of the hexagonal section across its flats, and it is preferably slightly less than the latter. Around the portion 23 of the shaft there is disposed a more or less U-shaped locking collar 25, the details of which are illustrated particularly in Figures 3 and 6. The collar 25 is designed to be readily positioned about section 23 of the shaft 18 or removed therefrom, and when the collar 23 is removed, the hub portion 6 of the closer arm 1 may be moved upwardly to be disengaged from the hexagonal section 22 of the shaft, thereby making possible the convenient adjustment of the relative position of the closer arm 1 and the shaft 18. The locking collar 25 is provided with an upstanding ear 27 which fits 50 into a suitable recess 28 in the intermediate bracket 13 and is preferably held in this position by a screw 29 or the like.

The portion of the shaft 18 which extends between the intermediate bracket 13 and the upper 55

bracket 14 is machined square so as to non-rotatably fit in a correspondingly shaped opening provided in a ratchet wheel 31 having suitable notches 32 formed at spaced intervals therein. A pawl 33 pivoted between the brackets 13 and 14 cooperates with the ratchet wheel 31 to hold the shaft 18 and with it the closer arm 1 in predetermined position against the tendency of the biasing spring 19 to rotate those elements in the direction required for closing the door.

It is not intended that the pawl 33 engage the ratchet every time the door is opened; it is used only when adjusting the tension of the spring 19, or when it is desired to hold the door open for a considerable period of time as when large quantities of material are trucked into or out of the cooling room.

When the described door closer is first mounted on a door structure, the spring is in a free untensioned condition. The arm assembly 4-5 is positioned on the hexagonal portion 22 of the short shaft so that the arm or rod 4 is disposed substantially parallel with the outside of the door 2 approaching its normal operative relation thereto as indicated in Figure 4. The arm is then swung outwardly or forwardly in the direction in which it moves when the door is opened, thereby winding up or applying tension to the spring. The arm may be swung to an angle of approximately 60 degrees open or any other position required to obtain the necessary spring tension. When the desired tension is obtained, the locking pawl 33 is moved into locking engagement with the ratchet 31 to lock the shaft and arm against return movement under the influence of the spring. Thereupon the arm assembly 4-5 is disengaged from the hexagonal shaft portion (the collar 25 having previously been removed) and adjusted to a position on the rounded shaft portion 23 whereupon the arm may be swung independently of the ratchet held shaft to its normal relation to the closed door. When the arm is thus adjusted to its normal relation to the door, it is again adjusted to inter-engagement with the hexagonal shaft portion 22. The collar 25 may then be replaced and the pawl disengaged from the ratchet so that the tension of the spring will cause the arm to bear against the door to hold it closed. It will of course be evident that any subsequent opening movement of the door will be resisted by the tension of the spring 19, and when the door is released the spring will close the door.

When the door is to be temporarily held in open position, it is merely necessary to open the door in the usual manner and then effect locking engagement of the pawl with the ratchet. As a practical matter this may be done from the inside of the door by passing the fingers of one hand through the space between the edge of the door and the adjacent door frame. It should be observed that in the majority, if not in all cases, the axes of the door hinges are spaced materially from the inner edge of the door frame as indicated in Figure 1 so that a material space is formed between the edge of the door and the door frame when the door is opened. Hence it is quite convenient to manipulate the pawl from the inside of the door as indicated.

When the door is to be again closed, the pawl 33 may be disengaged by merely pushing the door open to a slightly further extent with the result that the pawl is, in effect, cammed out of its locking engagement with the ratchet by the inter-engagement of the advancing edge of the ratchet tooth with the angularly arranged or curbed in-

side edge of the pawl. The pawl is preferably so mounted that it has no inherent tendency to swing in either direction, but will remain in whatever position it is left in, either as a result of hand manipulation or automatic adjustment as just described. Furthermore, the pawl tooth is preferably of such length and so shaped that the rocking movement imparted to the arm in the closing movement direction will not tend to cam the pawl to inoperative position, but will tend to more securely lock the pawl in its operative position. This action depends, of course, upon the relative angular arrangement of the outer edge of the pawl tooth and the corresponding face of the ratchet notch.

The described door closer may be used in connection with either right or left-hand doors without change in the door closer structure. For a right-hand door such as illustrated in Figure 1, the device is mounted with the arm projecting to the left of the body of the device and from its upper end. For a lefthand door the device is mounted with its arm projecting to the right of the body of the device and from its lower end. In other words, the device is merely inverted from the position shown in Figure 1 to adapt it for use in connection with a left-hand door. It should be noted that regardless of which position the device is used in, the arm assembly 4-5 is adequately supported by adequate bearings. When mounted as shown in Figure 1 for a right-hand door, the arm is supported against downward movement by the upper surface of the bracket part 12. When the device is mounted in inverted position for use on a left-hand door, the arm assembly 4-5 is supported on the bracket arm part 13 through the agency of the fixed collar 25. Hence the arm is adequately supported in either position in which the device may be mounted so that there is no increased tendency in one position for the arm assembly to work loose and become disengaged from the spring actuated shaft 18.

The detachable connection between the arm portion 4 and the head portion 5 is advantageous first in that it facilitates packaging of the device for shipping and storage purposes and second in that it permits removal of the laterally extending arm portion 4 especially when it is desired to render the door closer inoperative for an extended period of time during which it may be desirable to open and close the door without relying on the device for effecting closing. In such a case the arm may be swung to a 90 or 180 degree open position and there locked by means of the pawl 33. The rod 4 may then be unscrewed and laid aside for replacement when desired. The removal of the arm portion 4 avoids a necessity of leaving the arm in a projecting position under certain infrequently occurring circumstances when it is desired to make the door closer device inoperative. With the described arrangement the device may be made inoperative without letting out or otherwise tinkering with the tension of the spring 19, and the device may readily be restored to an operative condition by merely replacing the arm and disengaging the pawl from the ratchet.

The described door closer is simple and rugged in construction. It embodies relatively few parts, all of which may be manufactured without difficult manufacturing operations. The ruggedness of the device is incident not only to the employment of parts and materials well adapted for their respective purposes, but also to the particular arrangement described, especially in respect

of the location of the arm assembly 4—5 intermediate a pair of closely adjacent supporting brackets. The employment of a short stub-like shaft also is of material importance both in respect of 5 ruggedness of the device and in respect of the cost of construction thereof. In prior art devices where springs have usually been disposed about an extended shaft, considerable cost must be attributed to the long shaft length required. A further benefit from the described arrangement is 10 found in the fact that it is relatively easy to produce properly aligned bearing openings in closely adjacent bearing brackets such as required in this construction as distinguished from widely spaced bearing brackets required in the prior art constructions, especially where a long shaft is employed with a spring disposed about a portion thereof. Ease or smoothness of operation is also 15 assured by reason of the fact that the bearing openings may be accurately aligned as indicated.

Changes in the described construction may be made without departing from the spirit of the invention, the scope of which should be determined by reference to the following claims, the 25 same being construed as broadly as possible consistent with the state of the art.

I claim the following as my invention:

1. In a device of the class described, a pair of spaced frame members, a tube extending between 30 said frame members, a coil spring positioned within said tube and anchored at one of its ends to one of said frame members, the other of said frame members including a pair of spaced brackets integral therewith, a short shaft extending between and journaled upon said brackets, said short shaft being connected at one of its ends to the other end of said coil spring, and the portion of said short shaft which extends between said spaced brackets being divided into a flat 35 sided section and a section of substantially less cross sectional area than said flat sided section, a closer arm having a hub at one end thereof which is adapted to be disposed about and to lockingly engage said flat sided section of said shaft, and a collar normally positioned about said reduced area section of said shaft, said collar locking said hub in place upon said flat sided section of said shaft and being removable to permit said hub to be moved onto said reduced area section 40 in which position adjustment may be made in the angular position of said closer arm on said short shaft.

2. In a device of the class described, a pair of 45 vertically spaced frame members, a metallic tube extending between said frame members and affixed at each of its ends to one of said frame members, a coil spring positioned within said tube and anchored at one of its ends to the lower frame member, the upper frame member including a pair of spaced brackets integral therewith, a short shaft extending between and journaled upon said spaced brackets, said short shaft being connected at one of its ends to the other end of said coil spring and the portion of said short shaft which extends between said spaced brackets being divided into two dissimilar sections of substantially equal length, a closer arm having a hub at one end thereof which may be disposed about either of said dissimilar sections of said shaft intermediate said brackets, said hub having a width substantially equal to the length of each of said dissimilar sections and when positioned about one of said dissimilar sections being adapted to lockingly engage said shaft, said hub 55 and said shaft being independently movable when

said hub is positioned about the other of said dissimilar sections, and a locking collar normally positioned about the last mentioned dissimilar section in order that said hub shall normally be locked to said shaft, said collar being removable 5 to permit said hub to be moved to the other of said sections in which position adjustment may be made in the angular position of said closer arm on said shaft.

3. In a device of the class described, a pair of 10 vertically spaced frame members, a relatively rigid metallic tube extending between said frame members and affixed at each of its ends to one of said frame members, a coil spring positioned within said tube and anchored at its lower end to the lower of said frame members, the upper frame member including a pair of spaced brackets integral therewith, a short shaft extending between and journaled upon said brackets, said short shaft having a stub projection at its lower end for engaging and connecting with the upper end of said coil spring, the portion of said short shaft which extends between said spaced brackets being divided into a flat sided section and a cylindrical section of 25 reduced cross sectional area, a closer arm having a hub at one end thereof which is adapted to be positioned about and to lockingly engage said flat sided section, said flat sided section and said reduced section being of substantially equal 30 length and the width of said hub being substantially equal to the length of said sections, a generally U-shaped collar which is normally positioned about said reduced area section and which holds said hub in place upon said flat 35 sided section, said collar being removable to permit said hub to be moved to said reduced area section in which position adjustment may be made in the angular position of said closer arm on said short shaft, and a ratcheting mechanism 40 arranged at the upper end of said shaft for holding said arm in any desired position during the operation thereof.

4. In a device of the class described, a pair of 45 relatively closely spaced brackets, a short shaft extending between and journaled upon said brackets, the portion of said shaft lying between said brackets having a polygonal section and an adjacent section of less cross sectional area than said polygonal section, a closer arm 50 having a hub at one end thereof formed with a polygonal opening fitting said polygonal section of said shaft, a member normally straddling said adjacent section and locking said hub in position on said polygonal section, said member being attached to one of said brackets and bodily removable to permit said hub to be moved from said polygonal section to said adjacent section, in which latter position said hub may be turned on said shaft, and a coil spring attached to one 55 end of said shaft for biasing said shaft and said closer arm in a predetermined direction.

5. In a closer for refrigerator doors, a pair of spaced frame members, a coil spring extending between said frame members and anchored at 65 one of its ends to one of said frame members, the other of said frame members having a pair of spaced brackets integral therewith, a short shaft extending between and journaled upon said brackets, said short shaft being connected 70 at one of its ends to the other end of said coil spring, the portion of said shaft which extends between said spaced brackets comprising two sections, one having a larger transverse dimension than the other, a closer arm having an aper- 75

5 tured hub at one end thereof, said hub being disposed about said shaft intermediate said brackets and having an interlocking connection within its apertured hub with said shaft section of larger transverse dimension so as to prevent relative rotation of said arm and shaft, and a collar normally positioned about said other section of said shaft, and disengageable means for locking said collar in its normal position, said 10 collar serving to lock said hub in place upon said shaft section of larger transverse dimension and

being removable to permit said hub to be moved on to said other section in which position the arm may be rotated relative to said shaft to effect angular adjustment in the position of said arm on said shaft, said interlocking connection between said shaft section and hub being re-engageable in angularly adjusted position of said arm relative to said shaft, thereby to permit adjustment of the force of said spring when said arm is disposed in predetermined position. 10

WILLIAM J. KEENE.
